UNITED STATES PATENT OFFICE.

WARREN F. KAYNOR, OF WATERBURY, CONNECTICUT, ASSIGNOR TO WATERBURY BUTTON COMPANY, OF WATERBURY, CONNECTICUT, A CORPORATION OF CONNECTICUT.

DETACHABLE METAL BUTTON.

Application filed February 20, 1926. Serial No. 89,627.

This invention relates to detachable buttons for suits and uniforms, and more particularly to a hollow metal button, having a perforated top shell through which an underlying colored surface will be visible.

One object of this invention is to provide a hollow button of the above nature in which the colored surface is provided by a disc formed from material which matches that of the suit or uniform upon which the button is worn.

A further object is to provide a hollow button of the above nature which is adapted to be detachably mounted on one of the common solid buttons sewed to the garment.

A further object is to provide a detachable hollow button of the above nature which may be readily disassembled to permit the disc to be changed.

20 A further object is to provide a button of the above nature which will be simple in construction, inexpensive to manufacture, easy to manipulate, ornamental in appearance, and very efficient and durable in use.

25 With these and other objects in view, there has been illustrated on the accompanying drawings, one form in which the invention may be conveniently embodied in practice.

Fig. 1 represents a front view of the hollow metal button.

Fig. 2 is a side sectional view of the same, showing the button detachably mounted on a common coat button sewed to a garment.

Fig. 3 is a rear view of the hollow button as it appears when the locking slide is in locked position.

Fig. 4 is a similar view of the hollow button with the locking slide in unlocked position preparatory to detachment.

40 Referring now to the drawings in which like reference numerals denote corresponding parts throughout the several views, the numeral 10 indicates a hollow shell having a top portion 11, in which any suitable design

45 is formed, certain portions of said design being provided with perforations 12. The shell also has a downwardly extending cylindrical rim portion 13 terminating in a bottom inwardly-bent flange 14 which is

50 adapted to enclose and engage a back member 15 and a button locking slide 18. The back member 15 is provided with an arcuate or segmental section 16, said section having a rim 17 which is adapted to non-rotatably

engage the inner side of the rim portion 13 of the shell member 10.

The locking slide 18 is segmental in shape and is mounted to move under the back member 15, as clearly shown in Fig. 3. The locking slide also has a rim 19 which is 60 slidable in the rim 17. A finger-engaging lug 20 is provided near one end of the locking slide 18 for facilitating the manipulation thereof.

In order to cause the metal button to 65 blend with the material of a garment 21 on which the button is worn, a disc 22 of cloth or other suitable material, which matches the color of said garment, is located beneath the top portion 11 of the hollow shell 10, 70 and said disc 22 is visible through the perforations 12.

The hollow button is adapted to be detachably mounted upon a common solid button 23 of bone, ivory, rubber, or composition 75 secured to the garment 21 in any suitable manner as by threads 24.

In use, the common solid button 23 occupies most of the space in the interior of the hollow metal button and serves to support the cloth disc 22 and press it against the top portion 11 of the shell member 10. Whenever it is desired to change the disc 22, as when the button is to be used upon a different garment, it will only be necessary 85 to force the locking slide 18 to the right, from the position shown in Fig. 3 to that shown in Fig. 4. The hollow button may then be easily lifted off from the common sewed-on solid button 22. This will permit 90 the original cloth disc 22 to be removed and a new disc matching the new garment to be substituted. The metal button may then be again slipped over the coat button, after which the locking slide 18 will be moved 95 back to the left, from the position shown in Fig. 4 to that of Fig. 3.

It will be understood that while the present button is especially adapted for use on suits and uniforms, it may also be used 100 equally well on fancy dress clothing or other garments within the spirit of the invention.

One advantage of the present invention lies in the fact that one set of hollow buttons are adaptable for use upon any number of 105 suits or uniforms of various colors. In changing the button from one garment to another, it will be understood that it is only

necessary to substitute new discs which will match the color of the new garment.

A further advantage is that the use of a colored disc underlying the perforated design on the hollow button causes the design—an eagle in the present instance—to stand out in greater relief, particularly when the color of the disc matches that of the garment.

10 While there has been disclosed in this specification one form in which the invention may be embodied, it is to be understood that this form is shown for the purpose of illustration only, and that the invention is 15 not to be limited to the specific disclosure but may be modified and embodied in various other forms without departing from its spirit. In short, the invention includes 20 all the modifications and embodiments coming within the scope of the following claims.

Having thus fully described the invention, what is claimed as new, and for which it is desired to secure Letters Patent, is:

1. In a hollow button, a shell member having 25 perforations in its top surface, a disc visible through said perforations, said disc having a color matching the garment upon which the button is to be worn, said button being open in its bottom and adapted to be 30 detachably mounted on a common solid button sewed to said garment, said common button lying in contact with said disc and holding it against the perforated top of said hollow button.

2. In a hollow button, a shell member having 35 perforations in its top surface, a cloth disc visible through said perforations, said disc having a color matching the garment upon which the button is to be worn, said button being open in its bottom and adapted to be 40 detachably mounted on a common solid button sewed to said garment, said common button lying in contact with said disc and holding it against the perforated top of said hollow button.

3. In a hollow button, a shell adapted to be detachably mounted upon a common solid button sewed to a garment, a removable disc adapted to be located between the top of said shell and said solid button, and slidable 50 means for locking said solid button in said hollow shell, said disc having a color to match the material of said garment and being visible through the top of said shell.

4. In a hollow button, a shell adapted to 55 be detachably mounted upon a common solid button sewed to a garment, a removable disc adapted to be located between the top of said shell and said solid button, and rotatable means for locking said solid button in 60 said hollow shell, said disc having a color to match the material of said garment, the top of said shell being perforated whereby said disc will be visible therethrough.

In testimony whereof, I have affixed my 65 signature to this specification.

WARREN F. KAYNOR.
